UNITED STATES PATENT OFFICE.

ALBERT E. CARLISS, OF FLORAL PARK, NEW YORK, ASSIGNOR TO ACME AIR APPLI-
ANCE CO., INC., A CORPORATION OF NEW YORK.

AIR-PRESSURE GAUGE.

Application filed September 30, 1927. Serial No. 222,966.

This invention relates to an improvement in air pressure gauges, and particularly relates to air pressure gauges operating on the Bourdon gauge principle. It is addressed 5 particularly to means for restoring the indicating hand to its zero position with reference to a suitable index. It is addressed also to the solution of the problem of economy of construction and simplicity of operation.

10 The invention is illustrated in the accompanying drawings, wherein the individual parts are designated by numerals, like parts being referred to by like numerals.

Figure 1 is a plan view of the assembled 15 gauge, as viewed from the top.

Figure 2 is a plan view of the index and window supporting means, as viewed from the bottom.

Figure 3 is a detail cross section of a Bour- 20 don tube, taken on the line 3^a—3^a of Figure 4.

Figure 4 is a plan view with the top casing and index plate removed.

Figure 5 is a vertical section of Figure 4, 25 on the line 1, taken in the direction of the arrow 2.

Figure 6 is a detail vertical section of a block of metal shown in Figure 5 with cer- 30 tain associated elements.

Figure 7 is a vertical section of an index 35 plate.

Figure 8 is a vertical section of a window through which the index plate may be ob- 40 served.

Figure 9 is a vertical section of a casing in 45 which the gauge is mounted.

Figure 10 is a vertical section of a push button plate.

Figure 11 is a vertical section of a spring 40 and pin adapted to cooperate with said push button plate shown in Figure 10.

Figure 12 is a vertical section of the upper enclosing half of a casing for said gauge.

Figure 13 is the lower half of said external casing.

45 The construction and assembly of the several parts will now be described.

3 is a block of metal, preferably of rectangular form, having an extension 4. In the original process of manufacture, the axis of 50 said block 3 and extension 4 is the same. Under these conditions the extension 4 is readily turned in a lathe in the form indicated and is axially bored with a conduit as 5. An aperture as 6 is formed in the said exten- 55 sion 4, adapted to receive a suitable mecha-

nism 7 adapted to cooperate with a valve such as is commonly used in association with an inflated tire, so that when the mechanism 7 is pressed against a yielding element in said valve mechanism of the tire, the air under 60 pressure in the tire will flow into and through the conduit 5. When the construction of this extension 4 is completed, as indicated, the tube section thereof is preferably bent as indicated in the drawings, to accommodate 65 itself to a convenient application of the gauge to such a valve mechanism. The conduit 5, indicated in dotted lines in Figure 4, turns at right angles to its original course at 8, where it emerges from the block 3. 9 is a 70 Bourdon tube, the structure thereof being indicated in cross section in Figure 3. The base of this tube is secured to the block 3 at 10 so that it will cooperate with the conduit 8 mounted on the block 3. A hand 11 is pivot- 75 ally mounted on the block 3 by means of the screw 12, the same being held in resilient relation by a spring 13. 14 is an arm secured to the end of the Bourdon tube at 15. This arm is provided at the end thereof opposite to 80 that at which it is secured to said Bourdon tube with a hook 16, adapted to engage the index hand 11, so that when air under pres- 85 sure is introduced into the Bourdon tube 9, and the same is caused to expand according to well known principles, the hook 16 will engage the index hand 11 to cause the same to move in the arc of a circle, thereby co- 90 operating with the index 17, as illustrated in Figure 1.

All of the foregoing combination of ele- 95 ments is well known in the art, and requires no further explanation concerning either construction or operation. What follows deals particularly with mechanism for re- 100 storing said index hand to zero position with respect to said index.

The said block of metal 3 is provided with a slot in a plane longitudinal of and perpen- 105 dicular to the top surface of said block, said slot being indicated at 18. Said block 3 is also provided with three additional slots in parallel planes vertical and perpendicular to said plane in which said longitudinal slot is formed, said slots being indicated as 19, 20 and 21. Said block 3 is also provided with a vertical aperture as 22 leading from said slot 19 and adapted to receive a pin as 23. 24 is a crank arm bar provided at one end with a crank lever 25 adapted to be engaged by said 110

pin 23, and at the other end with a crank lever 26 adapted to engage the index hand 11. The crank lever bar 24 lies at the base of the slot 18 and is mounted for rotation therein. 27 is 5 a spring bar anchored to the block 3 at the point 28, and so bent as to fall within the slot 18 and bear upon the crank arm 24, as at 29, so as to maintain a spring tension on the crank arm bar 24 to hold the same in position 10 when the said crank arm bar is caused to operate by the engagement of the pin 23 with the crank 25, and the engagement of the crank 26 with the index hand 11, both of which might operate to cause the displacement of the said 15 crank arm bar 24, were it not for the tension of the said spring 27, operating to hold the same at the base of said slot 18.

The assembly of the operating mechanism may be described as follows: 30 is a cup-shaped element of rigid construction adapted 20 to contain the mechanism above described as an internal casing, said internal casing being pierced axially with an aperture as 31 to receive a push button to be hereafter described, 25 and 32 is another aperture in the wall of said internal casing, adapted to receive the air conduit 4. 33 is a push button adapted to lie in the aperture 31 of the interior casing 30. 34 is a helical spring adapted to rest in the cup-shaped seat of the push button 33, said push button and spring cooperating with the pin 23 heretofore described.

In assembling the device, the push button 33 is first placed within the aperture 31, the 35 spring 34 is caused to rest therein, and the pin 23 is introduced into the aperture 22. The assembled mechanism is introduced into the casing 30, the air pressure tube 4 passing through the aperture 32. It may be secured 40 therein by suitable means as the screw 35 introduced through the aperture 36. The index plate exhibited in plan view, Figure 2, and in section, Figure 7, is then introduced beneath the index hand 11, as indicated in 45 Figure 1 at 37. The index plate 37 is provided on the under side thereof with lugs as 38, adapted to engage corresponding apertures 39 in the periphery of the casing 30. 40 is another lug dependent from said index 50 plate, which is adapted to fall into the slot 21 and cooperate therewith in the matter of holding the said index plate in position. Said index plate is also provided with vertical lugs 41 struck up therefrom so as to form a bearing 55 for the transparent window plate shown in Figure 8. In the assembly said index plate 37 is introduced below the index hand 11, the lugs registering with the apertures as above indicated. The transparent plate 42 is then caused 60 to rest on the index plate at the points 43 and 44. In Figure 12 is shown a vertical section of the top enclosing cap of the casing, designated as 45. Said cap is provided with an aperture as 46 to serve as a window 65 through which to view the index plate 37 and

the index hand 11. It is also provided with an aperture 47 to allow for the passage of the air tube 4. In Figure 13 is shown the bottom enclosing cap of the casing designated as 48. This bottom enclosing cap is provided with the aperture 49, allowing access to the push button 33. 50 is an aperture cooperating with the aperture 47 to form an opening through which the air tube 4 may pass.

The operation of the device is as follows: 75 The whole assembly indicated in Figure 1 is manipulated manually so that the mechanism 7 is caused to engage the valve of an inflated element, such as a tire. By such action the valve carried by the tire is opened through the 80 compression of a suitable pin, and air under pressure is permitted to enter the conduit 5, and thence the Bourdon tube 9, causing the same to expand carrying with it the arm 14 so that the hook 16 engages the index hand 11, 85 causing the same to move over the index 17, which is viewed through the aperture 46, into a position as indicated in dotted lines in Figure 4, designated as 51. Under these conditions the gauge may be removed from the 90 valve seat of the tire, and the index hand remain in a fixed position with reference to the gauge 17 because of the tension of the spring 13. The problem now is one of restoring the index hand 11 to its zero position with reference to the index 17. This is accomplished by exerting manual pressure on the plate 33 to overcome the tension of the spring 34 and cause the plate 33 to engage the pin 23, thus forcing the pin 23 into engagement with the 100 crank arm 25, thus causing a rotation of the crank lever 24 and also a movement of the crank arm 26. The crank arm 26 will engage the index hand 11 and move the same back to a zero position with reference to the index 105 plate 17. The device is now ready for another application to the source of air pressure in the manner indicated.

It will be noted that the spring arm 29 bears on the crank rod 24 as previously stated with 110 a spring tension. Attention is called to the fact that this spring tension operates not only to hold the crank arm 24 in position but also to serve as a compensating element lying between said manual means of operation, to wit, 115 the push button, and also operates as a brake to prevent the recoil of the index finger where it is forced to zero position by the crank arm 26.

Claims:

1. In a pressure gauge of the Bourdon tube type, an integral block of metal having a Bourdon tube attached at its base and a conduit passing through said block and leading from a source of air pressure to the base of 125 said tube, an index hand pivotally mounted on said block, means operated by the movement of the said tube under air pressure to rotate said hand, a scale associated with said hand to indicate pressure as said hand trav- 130
